ELECTRIC CORD SOCKET

Dennis M. Geisel, 4203 Woodvale,
South Bend, Ind. 46614

Filed June 30, 1971, Ser. No. 158,654

Term of patent 14 years

Int. Cl. D13—03

U.S. Cl. D26—1 B

Fig. 1

Fig. 2

Fig. 3

Fig. 4

Fig. 5

Fig. 6

FIG. 1 is a perspective view of an electric cord socket embodying the present design;

FIG. 2 is a perspective view of the electric cord socket, showing the main cover in open position;

FIG. 3 is a front elevational view of the electric cord socket, showing the cord closure in open position;

FIG. 4 is a rear elevational view;

FIG. 5 is an elevational view of the side opposite that shown in FIGS. 1 and 2; and

FIG. 6 is a top plan view.

I claim:

The ornamental design for an electric cord socket, substantially as shown and described.
